(57) **CLAIM**

The ornamental design for a vaporizer cartridge, as shown and described.

DESCRIPTION

FIG. 1 is a top front perspective view showing a first embodiment of our new design for a vaporizer cartridge; FIG. 2 is a front elevational view of the first embodiment; FIG. 3 is a top plan view of the first embodiment; FIG. 4 is a left side view of the first embodiment; FIG. 5 is a right side view of the first embodiment; FIG. 6 is a bottom plan view of the first embodiment; FIG. 7 is a rear elevational view of the first embodiment; FIG. 8 is a top front perspective view showing a second embodiment of our new design for a vaporizer cartridge; FIG. 9 is a front elevational view of the second embodiment; FIG. 10 is a top plan view of the second embodiment; FIG. 11 is a left side view of the second embodiment; FIG. 12 is a right side view of the second embodiment; FIG. 13 is a bottom plan view of the second embodiment; and, FIG. 14 is a rear elevational view of the second embodiment. The broken lines in the drawings depict portions of the vaporizer cartridge that form no part of the claim.
